UNITED STATES PATENT OFFICE.

FREDERICK ALLAN BALLOU, JR., OF PROVIDENCE, RHODE ISLAND, ASSIGNOR TO B. A. BALLOU & CO., INC., OF PROVIDENCE, RHODE ISLAND, A CORPORATION OF RHODE ISLAND.

DESIGN FOR A GARMENT-SUPPORTING SHOULDER STRAP.

Application filed September 17, 1923. Serial No. 7,222. Term of patent 14 years.

To all whom it may concern:

Be it known that I, FREDERICK A. BALLOU, Jr., a citizen of the United States, residing in the city of Providence, county of Providence, and State of Rhode Island, have invented a new, original, and ornamental Design for a Garment-Supporting Shoulder Strap, of which the following is a specification, reference being had to the accompanying drawing, forming a part thereof.

The figure is a perspective view of a garment supporting shoulder strap, showing my new design.

This device is worn as an article of jewelry for use as a shoulder support for ladies' low-necked garments where it is wholly or partially exposed to view and is made of ribbon or narrow fabric having ornamental attaching clasps at its ends.

I claim:

The ornamental design for a garment supporting shoulder strap, as shown and described.

FREDERICK ALLAN BALLOU, JR.
